UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

MANUFACTURE OF GEARING FOR WINDOW REGULATORS.

Application filed October 23, 1925. Serial No. 64,470.

The invention relates to the manufacture of window regulators and has for one of its objects an improved method of manufacture whereby the efficiency and smoothness of operation of the window regulator are increased. Another object is to manufacture the window regulator at reduced cost. A further object is to manufacture by an improved method a gear member which forms part of the actuating mechanism of the window regulator. With these as well as other objects in view the invention resides in the novel features as more fully hereinafter set forth.

15 In the drawings:—

Figure 1 is a perspective view of a blank from which a gear member for a window regulator is formed;

20 Figures 2 and 3 are respectively side and edge elevations of a blank formed by the first step of my method;

Figures 4 and 5 are respectively side and edge elevations of a blank formed by the second step of my method;

25 Figure 6 is a cross section on the line 6—6 of Figure 4;

Figure 7 is an enlarged side elevation of a portion of Figure 4;

30 Figures 8 and 9 are respectively side and edge elevations of the completed blank;

Figures 10 and 11 are respectively side and edge elevations of a gear segment and lifter arm of a window regulator rigidly secured to each other.

35 Figure 12 is a side elevation of the complete window regulator;

Figure 13 is a side elevation showing the manner of rolling the blank;

40 Figure 14 is a cross section on the line 14—14 of Figure 13.

In one type of window regulator gearing is used in the actuating mechanism to raise or lower a window from the handle of the window regulator. As specifically shown in

45 Figures 12 and 13 the window 1 which is guided in a frame is adapted to be raised or lowered by means of the lifter arm 2 of the window regulator, there being a suitable connection between the outer end of this

50 lifter arm and the window. The inner end of this lifter arm is pivotally mounted at 3 upon the mounting plate 4. 5 is a gear member which in the present instance is a gear segment rigidly secured to the lifter

arm and having its teeth concentric with the pivot 3. 6 is a pinion meshing with the gear segment and adapted to be rotated by means of the handle 7.

With my method of manufacturing the gear segment I start with a sheet steel blank 8 of substantially uniform thickness and having a width preferably slightly greater than the diameter of the gear segment. This blank 8 is operated upon by a suitable punch which stamps out circular blanks 9 such as illustrated by the blank 9 in Figures 2 and 3. This blank has the peripheral roughed out oversized teeth 10, the axial opening 11, the symmetrically disposed openings 12 and 13 and the symmetrically disposed pairs of lateral projections 14 and 15. One of the openings 13 is preferably provided with a radial extension 16 between and on the radius connecting the axis of the blank and the axis of the opening.

This blank with several others is then operated upon by a suitable tooth-forming die 17 as shown in Figures 13 and 14, the blanks being separated and clamped between clamping members. This die is positively rotated and generates teeth 18 of maximum accuracy upon the blanks when these blanks are brought into engagement with the die. The blanks are accurately located relative to each other by means of pins which extend through the axial openings 11 and the openings 13 of the blanks, the pin extending through the openings having a longitudinal projection which is engageable in the extensions 16. In this manner the teeth of a number of gear blanks can be generated at the same time by engagement with a tooth-forming die. This die while generating the teeth compels the material forming the teeth to flow laterally in both directions and furthermore makes the bearing surfaces of the teeth more dense and hard as well as burnishes the same. In addition the die deflects the material at the bases of the interdental spaces to form the lateral projections 19 and hardens the radial outer surfaces of these lateral projections.

The gear blank after its teeth have been rolled is shown particularly in Figures 4, 5, 6 and 7.

After the teeth of a circular gear blank have been generated by rolling engagement with a tooth-forming die the circular blank

is severed to produce two like gear segments each segment having the openings 12 and 13, the lateral projections 14 and 15 and a recess equal to half the axial opening 11, the severing forming the edges 21 and 22 extending inwardly from opposite points of the periphery parallel to the diametrical line extending through the centers of the lateral projections 14 and 15 and equally on opposite sides of this line, these edges terminating at points to be connected by the edges 23 inclined at 45 degrees and passing through the axis of the blank. The circular gear blank is preferably operated upon prior to or at the time of severing to flatten the teeth and projections at the bases of the interdental spaces located in line with the lateral projections 14 and 15 and adjacent thereto. The gear segment as thus far illustrated is shown particularly in Figures 8 and 9.

After the gear segments have been formed each is rigidly secured to a sheet metal lifter arm of the window regulator, this step being preferably performed by spot welding and with the lifter arm and gear segment positively held in correct relative positions and the lifter arm bearing against the projections 14 and 15 through which the spot welding is preferably effected. The flattened tooth portion 20 of the gear segment affords clearance for the lifter arm so that the latter may lie against the gear segment.

From the above description it will be readily seen that I have devised a very efficient manner of forming window regulators and also for forming units which comprise a gear segment and lifter arm. With this method a material reduction in cost of manufacture is effected and at the same time a product of higher quality is secured.

What I claim as my invention is:

1. In the manufacture of gearing of window regulators, the method of making a toothed member which comprises punching a sheet metal blank to form a blank having oversized teeth and rolling the oversized teeth to final form.

2. In the manufacture of gearing of window regulators, the method of making a gear member which comprises punching out oversized teeth on a circular sheet metal blank, rolling the oversized teeth to final form and severing the circular blank with

the rolled teeth to form a plurality of gear members.

3. In the manufacture of gearing of window regulators, the method of making a gear segment which comprises punching a sheet metal blank of substantially uniform thickness to form a circular blank having oversized teeth, rolling the oversized teeth to final form and severing the circular blank with rolled teeth to form a plurality of like gear segments.

4. In the manufacture of a window regulator, the punching of a sheet metal blank to form a circular blank having peripheral oversized teeth, the rolling of the oversized teeth to final form, the severing of the circular blank with rolled teeth to form a plurality of like gear segments, and the securing of like lifter arms to the gear segments.

5. In the manufacture of a window regulator, the punching of a sheet metal blank to form a circular blank having peripheral oversized teeth, the rolling of the oversized teeth to final form, the severing of the circular blank with rolled teeth to form a plurality of like gear segments, the severing operation being such as to form straight spaced edges extending inwardly from opposite points of the periphery and lying parallel to each other and being connected at their inner ends by an inclined edge portion passing through the axis of the blank.

6. In the manufacture of a window regulator, the punching of a sheet metal blank to form a circular blank having peripheral oversized teeth, the rolling of the oversized teeth to final form, the severing of the circular blank with rolled teeth to form a plurality of like gear segments, the severing operation being such as to form straight spaced edges extending inwardly from opposite points of the periphery and lying parallel to each other and being connected at their inner ends by an inclined edge portion through the axis of the blank, the forming of projections upon each segment adjacent one of the straight edges and the welding of lifter arms to each gear member at the points where the projections extend from the gear members.

In testimony whereof I affix my signature.

STANLEY W. NICHOLSON.
